UNITED STATES PATENT OFFICE.

JACOB CLOOS, OF MILWAUKEE, WISCONSIN; ARTHUR R. BARRY ADMINISTRATOR OF
SAID CLOOS, DECEASED.

VALVE.

1,156,977.

Specification of Letters Patent.

Patented Oct. 19, 1915.

Application filed April 13, 1914. Serial No. 831,401.

To all whom it may concern:

Be it known that I, JACOB CLOOS, a citizen of the United States, residing at Milwaukee, in the county of Milwaukee and State of Wisconsin, have invented certain new and useful Improvements in Valves, of which the following is a specification, reference being had to the accompanying drawing, forming a part thereof.

10 This invention relates to mixing valves and the objects of the invention are to simplify the construction of such valves, to decrease the cost of construction of such valves, to increase the durability and reliability of such valves, to prevent water-hammer and chattering, and to reduce the size of such valves and thereby make them cheaper and more symmetrical in appearance in the manner to be hereinafter pointed 15 out and claimed.

Referring to the drawings accompanying this specification and forming a part hereof, on which drawings the same reference characters are used to designate the same 25 elements wherever they may appear in each of the several views, and which drawings illustrate an embodiment of this invention, Figure 1 is a plan view of the valve; Fig. 2 is a sectional view of the valve in elevation; 30 and Figs. 3, 4, 5 and 6 are sectional views of the valve taken on the line *a*—*a* on Fig. 2, looking in the direction indicated by the arrows, and showing the movable parts of the valve in different positions.

35 Referring specifically to the drawings, the reference numeral 1 designates the body of the valve which is hollow and provided with the hot water nipple 2 and the cold water nipple 3, respectively. The hot water thoroughfare 4 and the cold water thoroughfare 5 both communicate with the mixing chamber 6 through waterways 7 and 8 respectively. For convenience in machine operations in constructing the valves the waterways 7 and 8 are preferably enlarged in 40 diameter at their intersections with thoroughfares 4 and 5 as indicated by the reference numerals 9 and 10. Waterways 7 and 8 are open at their outer ends and are 45 closed by plugs 11 and 12 which are screw-threaded and engage with screw threads 13 and 14 on the interior ends of waterways 7 and 8. In constructing the valves the tap which forms screw threads 13 and 14 is run 50 into the waterways 7 and 8 beyond the en-

largements 9 and 10 to form screw threads 15 and 16 beyond said enlargements, the result being a uniformly screw threaded bore for each waterway interrupted by the enlargement.

Shoulders 17 and 18 are formed in waterways 7 and 8 to afford seats for packing 19 and 20 which preferably are made from vulcanized rubber or similar packing material. Screwthreaded, cylindrical bushings 21 and 22 engage with screw threads 15 and 16 and hold the packing members 19 and 20 in place against shoulders 17 and 18. These bushings are provided with longitudinal notches 23 and 24 which preferably taper or diminish in size toward the packings 19 and 20. The un-notched part of bushing 22 in the cold waterway 8 is shorter than the un-notched part of bushing 21 for a reason to be presently described.

An outlet 25 is screwed into a screw-threaded aperture 26 in the bottom of the body 1 for the escape of the water from mixing chamber 6 and the top of this outlet is provided with a table 27, communication 80 being afforded between mixing chamber 6 and the hollow interior 28 of the outlet 25 by apertures 29.

Above the table 27 is an aperture 30 which is screwthreaded to receive the guide plug 31 for the operating shaft 32. This shaft 32 is provided with a handle 33 secured thereto in the ordinary manner and is also provided with a crank disk 34 provided with crank-pin holes 35 and 36.

An index plate 37 is clamped between shoulder 38 on plug 31 and nut 39 and the bore 40 through plug 31 is counterbored at its upper end to receive packing 41 which is secured in the ordinary manner by follower 42 and nut 43. The valve stems 44 and 45 are screwthreaded and preferably provided with parallel-faced heads 46 and 47 to move between crank disk 34 and table 27 and crank pins 48 and 49 project upwardly from heads 46 and 47 into crank pin holes 35 and 36 in crank disk 34. The valve plugs 50 and 51 are globular shaped in mid-section to provide for their partial rotation in the opening and closing movements and they fit closely within bushings 21 and 22 to prevent movement sidewise and thus obviate chattering. They are provided with projections 52 and 53 on their seating sides to gradually shut off the flow of water through bushings 105 110

21 and 22 as the valve plugs approach their seats on the packings 19 and 20 and thus prevent water-hammer. The valve plugs are bored lengthwise and screwthreaded to 5 screw onto the stems 44 and 45 so that they can be adjusted thereon and they are counterbored to receive packing 54 and 55 which are held in place by followers 56 and 57 which are screwthreaded and screw onto the 10 stems 44 and 45. The plug 11 on the hot water side is provided with an adjustable stop screw 58, protected by a screw cap 59, which can be used to limit the opening movement of the hot water valve plug 50 to 15 prevent accidental scalding where desirable, as it will be apparent from an inspection of the drawings that when the said stop screw 58 is screwed in to prevent the full opening of the hot water valve plug 50 the cold water 20 valve plug 51 is prevented from entirely closing on the opening movement of the handle 33. The figures of the drawings show the screw stop 58 screwed out so that the hot water valve plug 50 can fully open 25 and the cold water valve plug 51 can fully close.

The adjustability of the valve plugs 50 and 51 on the valve stems 44 and 45 provide means for keeping the plugs water 30 tight even if the packings 19 and 20 wear because the operating mechanism is a form of crank mechanism and its throw can be lessened as the valve plugs are screwed farther onto the valve stems as will be readily 35 understood.

The handle 33 can be marked on one side "Cold" and on its other side "Hot" if desired.

The valve can be used in any situation or 40 for any purpose for which valves are used and while primarily intended to control hot and cold water its use is not limited to the ordinary installations where mixing valves are now used but on account of its simplicity 45 of construction and small cost it can be used in all situations where two valves or double valves are used.

It is preferred to make the valve plugs 50 and 51 from brass or other suitable metal 50 instead of rubber or such materials.

The operation of the valve is as follows. When the screw stop 58 is in the position illustrated by the drawings, and the handle 33 is moved so that its shorter end moves 55 from the position marked "off" to the position marked "hot" on the index plate 37, the valve plug 51 is moved away from packing 20 so as to permit the cold water to pass by it through notches 24 as clearly shown by 60 Fig. 4 of the drawings. With the parts in the positions shown by Fig. 4 of the drawings, the valve plug 50 has not moved out

of the un-notched part of bushing 21, consequently only cold water can be discharged. On further rotation of handle 33, valve plug 65 50 is moved farther away from packing 19 and hot water passes past the valve plug through notches 23 to mix with the cold water in the mixing chamber 6, as clearly shown by Fig. 5 of the drawings. On further rotation of handle 33 valve plug 50 is moved farther away from packing 10 and valve plug 51 is brought against packing 20, as clearly shown by Fig. 6 of the drawings, and with the parts in these positions 70 only hot water will be discharged. When the handle 33 is moved in the opposite direction the action of the valve plugs 50 and 51 will first permit both hot and cold water to pass (see Fig. 5), then will shut off the 80 hot water and permit only cold water to pass (see Fig. 4) and then will cut off the cold water as well (see Fig. 3) as will be readily understood.

What is claimed is:

1. In a valve, the combination of a body provided with a mixing chamber and waterways in communication therewith and an outlet therefrom, said waterways being provided with shoulders and screw-threads, of 90 packing seated against said shoulders, screw-threaded bushings screwed in said waterways against said packing and having their outer ends notched to regulate the passage of water, globular, metallic valve plugs fitting substantially water tight in said bushings to co-act with the notched ends thereof to regulate the passage of water, a crank disk, and valve stems connecting said valve plugs with said crank disk.

2. In a valve, the combination of a body provided with a mixing chamber and waterways in communication therewith and an outlet therefrom and a table in the mixing chamber, said waterways being provided 105 with shoulders and screw threads, of packing seated against said shoulders, screw-threaded bushings screwed in said waterways against said packing and having their outer ends notched, globular, metallic valve plugs fitting substantially water tight in said bushings to co-act with the notched ends thereof to regulate the passage of water, valve stems provided with crank pins connected with said valve plugs and resting upon said table, and a crank disk provided with crank pin holes to receive said crank pins.

In witness whereof I hereto affix my signature in presence of two witnesses.

JACOB CLOOS.
